UNITED STATES PATENT OFFICE

2,572,738

HAND CRIMPER

Martin G. Lovinggood, Odessa, Tex.

Application April 29, 1949, Serial No. 90,510

1 Claim. (Cl. 81—15)

1

This invention relates to a hand crimper especially designed for use in attaching a sheet metal take-off stub to a main duct for air conditioning and similar purposes.

In air conditioning and similar apparatus, it becomes necessary to insert a sheet metal take-off stub in a hole provided in a main air duct. The stub must be crimped down firmly all around inside of the main duct to hold the take-off stub firmly in place and to make it airtight. At present, the take-off stub is crimped to the main duct by holding a small dolly against a shoulder on the outside of the main duct and reaching inside and hammering the take-off stub down. The primary object of this invention is to provide a tool which will eliminate the time, trouble and effort expended in the present installation method.

Another object of the invention is to provide a hand crimper for use in attaching a sheet metal take-off stub to a main duct comprising a first lever, means for receiving the wall of the stub in said lever, a fixed jaw carried by said lever adjacent said means, a second lever pivoted intermediate the ends of said first lever, a movable jaw, and linkage connected to said second lever for urging said movable jaw towards and away from said fixed jaw.

These, together with various ancillary objects and features of the invention which will later become apparent as the following description proceeds, are attained by the device, a preferred embodiment of which has been illustrated by way of example only in the accompanying drawings, wherein:

Figure 1 is a side elevational view of the device illustrating its use in crimping a take-off stub to a main duct;

Figure 2 is a side elevational view of the device shown in open position;

Figure 3 is a bottom plan view of the device; and

Figure 4 is a top plan view of the movable jaw.

Specific reference is now made to the drawings. In the several views in the accompanying drawings and in the following specification similar reference characters indicate corresponding elements throughout.

Indicated at 10 is a main air duct having an aperture 12 adapted to receive a sheet metal take-off stub 14. The stub includes an annular shoulder 16 adapted to abut the duct 10. It becomes necessary to crimp the inner ends 18 against the inner surface of the duct 10 to secure

the stub to the duct, and the tool 20 has been provided for this purpose.

The tool includes a first lever 22 having a handle 24 and an elongated head 26. The head 26 includes an elongated slot 28 which is open at its forward end as at 30. As will be seen clearly in Fig. 1, the slot is adapted to receive the wall of the stub 14. Carried by the head adjacent the open end of the slot is a laterally extending fixed jaw 32 adapted to engage the shoulder 16.

Pivoted to the first lever 22 as at 34 is a second lever 36 which, as shown in Fig. 3, straddles the head 26 of the first lever. The second lever also includes a handle 38. Pivoted as at 40 to the upper end of the lever 36 is a link 42, which at its free end is pivotally secured as at 44 to a pair of short arms 46 that are in turn pivoted as at 48 to the head 26. The arms 46 carry a laterally extending movable jaw 50.

In use, the crimper 20 is slipped into the stub 14 so that the wall thereof is received in the slot 28, the fixed jaw 32 abutting the shoulder 16. The handles 24 and 38 are spread apart, as shown in Figure 2, to move the jaw 50 away from the jaw 32. In this position the jaw 50 engages the inner end 18 of the stub. When the handles are urged together, the jaw 50 moves towards the jaw 32, as shown in Fig. 1, crimping the end 18 against the inner surface of the main duct 10.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A hand crimper for use in attaching a sheet metal take-off stub to a main duct comprising a first lever having an elongated head and a slot extending longitudinally through substantially the entire length of said head and opening through the free end thereof, said slot being adapted to receive the annular wall of a take-off stub, a fixed jaw at the free end of said head and extending laterally thereof, a second lever pivoted intermediate its ends to said first lever, a first link pivoted intermediate its ends to the free end of said head, a second jaw at one end of said first

link and opposite said fixed jaw, and a second link terminally pivoted to said second lever and to the other end of said first link.
